UNITED STATES PATENT OFFICE.

JOSEPH B. CRANE, OF PITTSBURGH, PENNSYLVANIA, ASSIGNOR TO GEORGE T. LADD,
OF PITTSBURGH, PENNSYLVANIA.

BAFFLING FOR BOILERS.

Application filed October 24, 1923. Serial No. 670,489.

To all whom it may concern:

Be it known that I, JOSEPH B. CRANE, residing at Pittsburgh, in the county of Allegheny and State of Pennsylvania, a citizen 5 of the United States, have invented or discovered certain new and useful Improvements in Baffling for Boilers, of which improvements the following is a specification.

It is the usual practice to so construct and 10 arrange the baffles in boilers that the direction of flow of gases through the boiler is reversed or changed through an angle of approximately one hundred and eighty degrees, two or three times. This reversal 15 causes a greater retardation in the rate of flow than the tubes themselves, and hence in constructing a boiler provision must be made either by the construction of the stack or the employment of exhaust fans for producing a sufficient drop of pressure between 20 the furnace and the gases outlet, to overcome not only the retardation due to the resistance encountered by the gases flowing across and along the tubes and that due to 25 the reversal of the flow when operating at normal rating, but also to cause the increased flow necessary to operate the boiler above rating. The construction of a stack capable of overcoming the necessary drop 30 of pressure or the employment of a fan of sufficient capacity, adds greatly to the cost of installation. It is of course possible to obtain an increase of rating without increasing the volume or weight of gases flowing 35 through the boiler, by increasing the temperature of the gases generated. This method is decidedly objectionable as it involves a great increase in the amount of fuel consumed, and a consequent increase in operating 40 expenses.

The invention described herein has for its object the so baffling of the boiler that efficient contact of the hot gases with the heating surfaces is attained without reversal in 45 the direction of flow of the gases, and with slight change in the direction of flow. The invention is hereinafter more fully described and claimed.

In the accompanying drawings forming 50 a part of this specification Fig. 1 is a sectional elevation of a vertical water tube boiler baffled as described and claimed herein; Fig. 2 is a sectional plan view on a plane indicated by the line II—II, Fig. 1; Figs. 55 3, 4, 5, and 6 are detail views showing dif-

ferent arrangements of baffles and manner of constructing the same.

In combining the improvement claimed herein with vertical water tube boilers, the baffles extend from the lower to the upper 60 drums or the entire length of the tubes, and parallel therewith. In the embodiment of the invention shown herein in Fig. 1, the baffles are arranged in line with the last series of tubes forming the several banks of tubes 1, 2, 3, but the invention claimed herein is not limited to any specific location of the baffles transverse of the direction of flow of the gases from the combustion chamber to the stack. To permit of the flow of gases 65 to the stack, opening or ports 4 are formed through the baffles. As is well known to those skilled in the art, a boiler is at times operated at normal rating and frequently considerably above normal rating, and when 70 operated above rating the volume of gases generated and passed through the boiler is very much greater than when the boiler is operated at normal rating. Hence the openings 4 through the first baffle or the one adjacent to the combustion chamber, are made of such dimensions as to permit the passage of gases which would be generated when the boiler is operated at an average rating between normal and the highest rating at which 75 the boiler is designed to be operated. In order to break up the streams of gases flowing through the openings in a baffle, and so divert such streams as to ensure the circulation of the gases among the tubes the openings in succeeding baffles are arranged out of alinement with the openings in the preceding baffle. As for example, in the embodiment shown in Figs. 1 and 2, the openings in 80 the second baffle are arranged out of alinement with the openings in the first baffle, and the openings in the third are arranged out of alinement with the openings in the second baffle.

As the gases flowing between the tubes are 85 progressively cooled and their volumes decreased, the total area of the openings in each succeeding baffle are preferably proportionally less than that of the openings in the preceding baffle. In vertical boilers, and in 90 the term "vertical boilers" are included both the Wicks Sterling and the Ladd or Milne types, the fuel bed is adjacent to the lower ends of the first bank of tubes, as shown in Fig. 1, and in order to prevent 95 100 105 110

a tendency of the gases to short circuit through the lower openings in the baffle, such openings may be made of relatively small areas and the areas progressively larger towards the upper ends of the baffles. This proportioning of the areas of the openings in connection with the tendency of the hot gases to pass upward, would tend to draw the gases away from the smaller openings of the lower end, but as the openings at the upper ends will permit of the passage of only certain proportions of the volumes generated, there will always be an efficient flow of gases through the lower openings. Such a construction of baffles and relative proportioning of openings in each will ensure a substantially uniform flow of gases and consequently equal application of heat in all points along the length of the tubes in front of such baffle.

As shown in Figs. 2 and 6, the baffles may be formed by filling the spaces between alternate pairs of tubes with suitable material such for example as wedge shaped blocks 5, as shown in Fig. 6. In such a construction the openings for the passage of gases will extend the entire distance between the drums. But as in such construction it may be difficult to control the distribution of the gases vertically, it is preferred to construct the baffles as shown in Fig. 5. As shown thereon, the spaces between all of the tubes of a row or series are so filled or closed as to have openings at suitable intervals horizontally and vertically. A desirable means for forming such a baffle consists in employing wedge shaped blocks 6. These blocks are formed with grooves in one edge so as to fit around the tubes while the opposite edge is inclined. These blocks are so constructed that when placed in reversed position with their inclined faces in contact and their ends in alinement, the combined width of the blocks will be greater than the distance between walls of adjacent tubes. In arranging these blocks in position, a block is inserted between adjacent tubes with its larger end resting on the lower drum and the groove in its edge engaging a tube. A second block in reversed position is then inserted between the first block and the other tube, but as the combined widths of the blocks is greater than the distance between the tubes, this second tube will not move down so that its lower end will bear on the drum, hence there

will be an opening formed. The third block 6^b will be arranged so that its larger end will rest on the larger end of the block 6^a and the block 6^c inserted in the same manner as the block 6^b, thereby forming an opening of double the area of the opening at the lower end of the block 6^a. By thus forming the baffle, a plurality of openings are formed alternating horizontally and vertically. In case smaller openings are desired, the blocks forming the baffle may be arranged as shown in Fig. 4. As shown in Fig. 5, one of the members as 7 forming a pair of blocks may be made shorter than the member 6.

It is characteristic of the improvement claimed herein that although the general direction of flow of gases from the combustion chamber to the stack is at right angles to the tubes forming the heating surfaces, their lines of movement are more or less directed from straight lines by the relative positions of the openings in the baffles, and hence their flow may be more correctly termed sinuous but in no case will the lateral diversion from the general line of flow approach a reversal of the direction of flow.

I claim herein as my invention:

1. A vertical water tube boiler having in combination vertical banks of tubes, a combustion chamber and an outlet for gases so arranged on opposite sides of the banks of tubes that the line of flow of hot gases will be at an angle to the tubes and baffles extending parallel with and the entire widths of the banks of tubes and having openings therethrough the openings in adjacent baffles being out of alinement and the area of said openings increasing from points adjacent to the combustion chamber.

2. A vertical water tube boiler having in combination therewith vertical banks of tubes, combustion chamber and an outlet for the gases so arranged on opposite sides of the bank of tubes that a line of flow of the gases will be at an angle to the tubes, and baffles consisting of a plurality of pairs of longitudinally tapering blocks arranged between adjacent tubes, a block of each pair being spaced from the vertically alined block on the adjacent pair.

In testimony whereof, I have hereunto set my hand.

JOSEPH B. CRANE.
